UNITED STATES PATENT OFFICE

HAROLD S. LOOMIS, OF WILKINSBURG, AND HOWARD A. THOMPSON, OF EDGEWOOD BOROUGH, PENNSYLVANIA, ASSIGNEES TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed May 15, 1928. Serial No. 278,008.

Our invention relates to railway traffic controlling apparatus, and particularly to apparatus of the type comprising train carried governing means controlled by devices located at intervals along the trackway.

One feature of our invention is the provision in apparatus of the type described of train carried governing means which is effective at times to cause a service application 10 of the brakes which can be released by the engineman only after the expiration of a time interval which is of such length as to insure that the train speed has been reduced to a comparatively low value.

Another feature of our invention is the provision of means for preventing an automatic application of the brakes, even under unsafe traffic conditions, if the speed of the train is below the value from which the service application can bring the train to a full stop short of the hazard which is rendering traffic conditions unsafe.

Other features and advantages of our invention will appear as the description proceeds.

We will describe two forms of apparatus embodying our invention, and will then point out the novel features thereof in claims.

In the accompanying drawings, Figs. 1 and 2 when placed end to end with Fig. 1 on the left comprise a diagrammatic view showing one form of trackway apparatus embodying our invention. Fig. 3 is a view, partly diagrammatic and partly in section, showing one form of train carried governing means suitable for cooperation with the trackway apparatus illustrated in Figs. 1 and 2 and also embodying our invention. Fig. 4 is a diagrammatic view showing in modified form a portion of the apparatus shown in Fig. 1, and also embodying our invention.

Similar reference characters refer to similar parts in each of the several views.

Referring first to Figs. 1 and 2, the reference characters 1 and 1^a designate the rails of a stretch of railway track over which traffic normally moves in the direction indicated by the arrow. These rails are divided, by means of insulated joints 2, to form a plurality of successive track sections A—B,

B—C, C—D, D—E, and E—F. Each track section is provided with a source of track circuit current, here shown as a transformer designated by the reference character 4 with an exponent corresponding to the location and having its secondary connected across the rails adjacent the exit end of the section. The primary of each track transformer 4 is constantly supplied with alternating current from a suitable source of energy such as a line transformer designated by the reference character 7 with an exponent corresponding to the location and supplied with energy from an alternator M over line wires 3. In order to simplify the drawing we have omitted the wires which connect the terminals of the secondary of the several line transformers with the apparatus to which these secondaries supply energy. The terminals of each line transformer secondary are designated by the reference characters X and Y with exponents corresponding to the location, and similar reference characters are applied to the terminals of the various circuits.

Each track section is also provided with a track relay designated by the reference character R with an exponent corresponding to the location and connected across the rails adjacent the entrance end of the section. One rail 1^a of each section is provided with an additional insulated joint 2^a at a point in the rear of the exit end of the section. The primary of a transformer 5 is connected across each such joint 2^a and the secondary of each such transformer 5 is connected through a rectifier 6 with the winding of a relay designated by the reference character J with an appropriate distinguishing exponent. It will be plain, therefore, that each track section is provided with a track circuit comprising the secondary of a track transformer 4, the winding of track relay R, the primary of a transformer 5, and the rails of the section in series. It follows that when the section is unoccupied, the track relay R is energized and the associated relay J is also energized. When a train enters the section, the track relay immediately becomes de-energized but the relay J for that section remains energized until the train passes insulated joint 2^a.

whereupon relay J opens and remains open until the train has passed out of the section.

Each section is also provided with a polarized home relay and a home repeater relay designated by the reference characters H and G, respectively, with suitable distinguishing exponents. Referring particularly to relay H^A, this relay is at times supplied with energy from a transformer 12^B located at point B. One circuit for this relay passes from the upper terminal of the secondary of transformer 12^B, through front contact 14 of relay G^B, wire 15, front contact 16 of relay R^B, wire 17, front contact 18 of relay J^B, wire 19, front contact 20 of relay R^A, winding 8 of relay H^A and wire 20^a, to the midpoint of the secondary of transformer 12^B. Winding 9 of relay H^A is constantly connected with terminals X^A and Y^A of transformer 7^A and when the circuit just traced is closed, relay H^A is energized in one direction, which I will call the normal direction, so that its contacts are swung to the left. When relay G^B is de-energized, however, the lower terminal of the secondary of transformer 12^B is connected with wire 15, over back contact 14 of relay G^B and under these conditions, the relative polarity of the current supplied to the winding 8 of relay H^A is reversed, so that the relay is energized in its reverse direction to swing its contacts to the right. When relay H^A is energized in either its normal or reverse direction, current is supplied to relay G^A, over contact 31 of relay H^A, so that relay G^A is energized. When relay H^A is de-energized, however, the circuit for relay G^A is interrupted and the latter relay is de-energized. The circuits for each of the remaining relays H and G are similar to those just described for relays H^A and G^A and will be understood from the drawing without further explanation.

Each track section is also provided with a polarized distant relay designated by the reference character Q with a suitable exponent and comprising two windings 10 and 11, one of which, 11, is constantly supplied with alternating current from terminals X^A and Y^A. Associated with each distant relay Q is a distant repeater relay designated by the reference character P with an appropriate exponent. Referring particularly to relay Q^A, this relay is at times supplied with energy from a transformer 19^B, the primary of which is constantly connected with terminals X^B and Y^B of line transformer 7^B. One circuit for relay Q^A may be traced from the upper terminal of the secondary of transformer 19^B, through wire 132, front contact 21 of relay P^B, wire 22, front contact 23 of relay G^B, wire 24, normal contact 25 of relay H^B, wire 26, front contact 27 of relay G^A, wire 28, winding 10 of relay Q^A and wire 29 to the midpoint of the secondary of transformer 19^B. When the circuit just traced is closed,

relay Q^A is energized in the normal direction to swing its contacts to the left. When relay P^B is de-energized, however, the lower terminal of the secondary of transformer 19^B is connected with wire 22, over wire 30 and back contact 21 of relay P^B, and under these conditions the polarity of the current supplied to relay Q^A is such that the relay is energized in its reverse direction to swing its contacts to the right. Relay P^A is energized when relay Q^A is energized in either direction but is de-energized when relay Q^A is de-energized. The remaining relays Q and P are provided with circuits similar to those just described for Q^A and P^A.

Associated with each section is a governing device designated by the reference character L with a suitable exponent and arranged to cooperate with train carried governing means as will be described in detail hereinafter. Each of the devices L is biased to an effective position (see L^B) but may be moved to an ineffective position (see L^A) by means of operating mechanism not shown in the drawing. Each device L also comprises a contact 51 which is arranged to be closed when the device occupies its ineffective position but to be open when the device occupies its effective position. One form of device operating in the manner described is disclosed and claimed in Letters Patent of the United States No. 1,591,988, issued July 13, 1926, to William C. McWhirter, for railway traffic controlling apparatus.

Each of the devices L is provided with a main operating circuit and a number of auxiliary circuits. Referring particularly to device L^A, the main circuit for this device may be traced from terminal X^A, over front contact 33 of relay R^A, wire 34, front contact 35 of relay G^A, wire 36, normal contact 37 of relay H^A, wire 38, front contact 39 of relay P^A, wire 40, normal contact 41 of relay Q^A, and wires 42, 43, 44, 45, 46, 47, and 48, through the operating mechanism of device L^A to terminal Y^A. When this circuit is closed the device L^A occupies its ineffective position but if the circuit is, for any reason interrupted, the device moves to its effective position.

Associated with each section is a trackway signal which in the form shown is a light signal designated by the reference character S with a distinguishing exponent and comprising three groups or "arms" b, m, and t of light units which are adapted to project beams of distinctive colors. For example, the top arm t of each signal S comprises a red unit, a yellow unit, and a green unit. The middle arm m of each signal comprises three red units, two yellow units, and one green unit, and the bottom arm b of each signal comprises two red units and one green unit. Each signal S is controlled in part by

a light-out relay designated by the reference character K with an appropriate exponent.

As shown in the drawing, the section to the right of point F is occupied by a train indicated diagrammatically at Z. As a result 5 the track relay R^F is de-energized. The circuit for relay H^F is open at front contact 20 of relay R^F and the relay H^F is de-energized. The repeater relay G^F is also de-energized, and since front contact 27 of relay G^F is open, 10 relay Q^F is also de-energized and relay P^F is open. Under these conditions, the main circuit for device L^F is open so that this device occupies its effective condition. Since 15 front contact 59 of relay R^F is open, the circuit for light-out relay K^F is open and this relay is de-energized. Under these conditions, current flows from terminal X^F, over 20 back contact 53 of relay K^F, wire 54, a red unit of the middle arm m of signal S^F, wire 55, a red unit of the bottom arm b, wires 56 and 57, a red unit of the top arm t of signal S^F, and wire 58 to terminal Y^F. The indication presented by the signal under these 25 conditions is three red lights in a vertical row.

The current supplied to section E—F transformer 4^F energizes relay J^F and relay R^E but the circuit for relay H^E is open at front contact 16 of relay R^F so that relay H^E 30 is de-energized. Relays G^E, Q^E, and P^E are also de-energized. The main circuit for device L^E is therefore open and this device occupies its effective position. Under the 35 conditions just described, current flows from terminal X^E, over front contact 59 of relay R^E, wire 60, winding of relay K^E, wire 61, back contact 63 of relay G^E, wire 64, a yellow unit of middle arm m of signal S^E, wires 65 and 66, a red unit of the bottom arm b, wires 40 67 and 68, a red unit of the top arm t, and wire 69 to terminal Y^E. The aspect now displayed by signal S^E is a red light over a yellow light over a red light.

Relays J^E and R^E associated with section 45 D—E are both energized and since relay G^E is de-energized, current is now supplied to relay H^E to energize this relay in its reverse direction. Relay G^D is therefore energized but relays Q^D and P^D are open. The main 50 operating circuit for devices L^D is open and the device occupies its effective position. The aspect now displayed by signal S^D comprises a red light over a yellow light over a green light, the circuit passing from terminal X^D, over front contact 59 of relay R^D, wire 60, winding of relay K^D, wire 61, front contact 63 of relay G^D, wire 62, reverse contact 70 of relay H^D, wire 71, a yellow unit 55 of the middle arm m of signal S^D, wire 72, a green unit of the bottom arm b, wire 68, a red unit of the top arm t and wire 69 to terminal Y^D.

Referring now to section C—D, relays J^D and R^C are both energized. Since relay G^D 60 is energized, the current supplied to relay H^C

energizes this relay in its normal direction and relay G^C is energized but relays Q^C and P^C are both de-energized. Under these conditions the circuit for device L^C is open so that this device occupies its effective position. The circuit for signal S^C under these 70 conditions may be traced from terminal X^C, over front contact 59 of relay R^C, wire 60, winding of relay K^C, wire 61, front contact 63 of relay G^C, wire 62, normal contact 70 of relay H^C, wire 73, back contact 74 of relay P^C, wire 75, a red unit of the middle arm m of signal S^C, wires 76 and 77, a yellow unit of the top arm t, wires 78 and 79, a red unit of the bottom arm b, and wire 80 to terminal Y^C. The aspect displayed by signal S^C under these conditions therefore is yellow over red.

Relays R^B and J^C are both energized and relay H^B is energized in its normal direction. Relay G^B is also energized. Since relay H^C is energized in its normal direction to close contact 25 and since front contact 23 of relay G^C is also closed, a circuit is completed for relay Q^B. Relay P^C is de-energized, however, so that the current supplied to relay Q^B energizes this relay in its reverse direction. Relay P^B is energized, but the main circuit for device L^B is open and this device occupies its effective position. With the apparatus at point B in the condition in which it is illustrated in the drawing, the signal S^B displays an indication comprising yellow over green over red, the signal circuit passing 90 from terminal X^B, over front contact 59 of relay R^B, wire 60, winding of relay K^B, wire 61, front contact 63 of relay G^B, wire 62, normal contact 70 of relay H^B, wire 73, front contact 74 of relay P^B, wire 81, reverse contact 82 of relay Q^B, wire 83, a green unit of middle arm m of signal S^B, wire 77, a yellow unit of top arm t, wires 78 and 79, a red unit of bottom arm b, and wire 80 to terminal Y^B.

Relays R^A and J^B associated with section A—B are energized and relay H^A is energized in the normal direction. Relay G^A is therefore picked up. Since relay P^B is now energized, relay Q^A is energized in the normal direction and relay P^A is also energized. It will be seen, therefore, that the main circuit first traced for device L^A is now closed and that this device occupies its ineffective position. Furthermore, a circuit is now closed for signal S^A from terminal X^A, over front contact 59 of relay R^A, wire 60, winding of relay K^A, wire 61, front contact 63 of relay G^A, wire 62, normal contact 70 of relay H^A, wire 73, front contact 74 of relay P^A, wire 81, normal contact 82 of relay Q^A, wire 84, a green unit of the top arm t of signal S^A, wire 85, a red unit of the middle arm m, wires 86 and 79, a red unit of the bottom arm b, and wire 80 to terminal Y^A. The aspect displayed by this signal is therefore green over red over red.

In describing the circuits of the various signals, we have applied the same reference characters to corresponding parts at each location to facilitate comparison of the signal circuits at the several locations.

It will be apparent that at each location, except the location immediately in rear of an occupied section, the light-out relay K is included in series with the several units of the signal S which are then energized. The parts are so proportioned that should any one of the light units burn out, the light-out relay K would become open circuited and de-energized, thereby closing, at that location, a circuit similar to that previously traced for signal S^F so that under all conditions a burned out light unit will cause the corresponding signal to display the most restrictive signal indication.

The trackway apparatus illustrated in Figs. 1 and 2 is suitable for cooperation with train carried governing means which is responsive to the positions of the devices L located in the trackway. One form of train carried apparatus which will cooperate in this manner is illustrated in Fig. 3. In this view the reference character N designates an engineman's brake valve of the usual and well known form for controlling the usual automatic brake applying apparatus on the train through the medium of the brake pipe 104. Associated with the valve N is an application slide valve comprising a piston 111 which is urged to an upper position by a spring 113. Fluid under pressure, usually air, is constantly supplied to the upper side of the piston 111 from a source of fluid pressure not shown in the drawing through pipes 87 and 110. Pressure is also supplied to the lower side of piston 111, through a restricted orifice 112 in the piston. The combined forces of spring 113 and the pressure on the lower side of piston 111 normally hold this piston, and the slide valve controlled thereby, in their upper positions, in which they are illustrated in the drawing. Under these conditions, fluid pressure is supplied to the brake-pipe from pipe 87, through pipe 88, the usual feed valve 89, pipe 90, port 91 in the engineman's brake valve, pipe 101, port 102 in the application slide valve, and pipe 103 to brake pipe 104. The brake-pipe 104 is also connected to chamber 97 beneath the usual equalizing valve 98. The chamber 95 above the equalizing valve 98 is constantly connected with an equalizing reservoir 96, and chamber 95 and reservoir 96 are both connected through pipe 94, port 93 in the application slide valve, pipe 92, and port 91 with pipe 90. Under normal conditions, therefore, the equalizing reservoir 96 is charged and the same pressure exists on both sides of the equalizing valve 98 so that valve 99 is closed. A reduction limiting reservoir 106 is connected, through pipe 107 and port

108 with atmosphere at port 109. A pipe 114 is constantly connected with the chamber beneath the piston 111. When this pipe is vented to atmosphere, therefore, the pressure above the piston 111 over-balances the pressure beneath this piston and moves the piston to a lower position. When this occurs, the closing of port 102 disconnects the brake pipe from pipe 101. Furthermore, port 93 now connects the equalizing reservoir with the reduction limiting reservoir and blanks port 109. The pressure in the equalizing reservoir is therefore reduced and the equalizing valve 98 moves upwardly to vent the brake pipe 104 through the restricted orifice 100, until the pressures on the two sides of the piston are equal, whereupon the valve returns to its original position to prevent further bleeding of the brake pipe. When the piston 111 is in its lower position, port 116 connects pipe 114 through pipe 115 and port 116, pipe 117, and port 118 of the engineman's brake valve with atmosphere at pipe 119. The port 118 is open at all times except when the engineman's brake valve occupies the lap position. It follows that after the piston 111 has moved to its lower position to cause a brake application, the piston remains in its lower position until the valve N has been moved to the lap position. The parts are so proportioned that when the piston 111 moves to its lower position, the reduction in brake pipe pressure is such as to cause a service application of the brakes. It should be noted that when the piston 111 occupies its lower position it is impossible to charge the brake pipe through the engineman's brake valve because pipe 92 and pipe 101 are both blanked at the slide valve controlled by the piston.

Pipe 114, which controls the piston 111, is in turn controlled by a valve device comprising a main valve 121 having its lower end terminating in a piston 123 and biased to the position in which it is shown in the drawing by a spring 122. When the valve is in this position, chamber 126 is disconnected from a passage 133 which leads to atmosphere. The valve 121 is hollow, and its lower end contains a pilot valve 128 which is normally held closed by a spring 127. The chamber 126 is connected with a reservoir 124 through holes 125 drilled in the valve 121, and the chamber 126 is also connected, through pipe 141 with a reservoir 120 and pipe 114. Under normal conditions, then, reservoir 120 and reservoir 124 and chamber 126 are all charged with fluid pressure which is admitted to pipe 114 through restricted orifice 112 in piston 111. Under these conditions, the spring 122 holds the valve 121 in its lower position and valve 128 is also closed.

The reference character 129 designates a plunger which is arranged to be moved upwardly when the train passes a trackway de-

vice L in its effective position but the plunger 129 is not operated when the train passes a trackway device L in its ineffective position. When the plunger 129 is moved upwardly, it 5 engages the lower end of the pilot valve 128, moving this valve against the bias of spring 127, and admitting air from reservoir 124 through the hollow stem of valve 121 to the chamber 130 below piston 123. As a result, 10 the piston 123, and valve 121 carried thereby, are forced upwardly against the bias of spring 122. This movement of valve 121 closes holes 125 and traps the pressure in reservoir 124 and chamber 130 thereby holding 15 the piston 123 in its upper position. The piston 123 carries a pivoted pawl 131 which is effective when the piston 123 is in its upper position to hold the pilot valve 128 open. When valve 121 is moved upwardly, chamber 20 126 is connected with atmosphere through passage 133, thereby venting pipe 141 to atmosphere, and emptying reservoir 120 and the chamber beneath piston 111 of the application slide valve. This operation causes a 25 service application of the brakes in the manner already described. The pressure in reservoir 124 which is trapped by the movement of valve 121 upwardly to close holes 125, holds the piston 123 in its upper position long 30 enough to insure that the reservoir 120 is completely discharged. The pressure trapped in reservoir 124 gradually leaks off, however, through the guides of the valve 121 and the pilot valve 128, and after the expiration of 35 a time interval, spring 122 again restores the valve 121 to the position in which it is illustrated in the drawing, thereby allowing valve 128 to close. If, now the engineman moves valve N to the lap position, pressure from 40 pipe 110 passes through the restricted orifice 112 in piston 111 and gradually charges reservoirs 120 and 124. After the expiration of a time interval, such for example, as 15 seconds, the pressure below piston 111 is increased to 45 a sufficient value to permit this pressure plus the effect of spring 113 to restore the piston 111 to the position in which it is illustrated in the drawing thereby connecting the reduction limiting reservoir 106 to atmosphere, and re-charging the brake pipe to its original 50 value.

It will be plain from the foregoing that when the train passes a trackway device L in its effective position, the operation of 55 plunger 129 initiates a service application of the brakes and that this automatic application can be released only after the expiration of the time interval required to charge reservoir 120 and return piston 111 to its upper 60 position. If, prior to the restoration of the piston 111 to its upper position, the train passes a second trackway device L in its effective position, the plunger 129 is again raised, and again vents the reservoir 120 to atmosphere so that the time interval required to

charge reservoir 120 is re-established. It follows that the brakes can be released only at the expiration of the full time interval of 15 seconds after the last actuation of the valve 128 by a trackway device L.

Referring now also to Figs. 1 and 2, we will assume that a train provided with the apparatus illustrated in Fig. 3 passes through the stretch of track shown in Figs. 1 and 2. When this train passes device L^A, the plunger 129 is not operated because this device is in its ineffective position. When the train enters section A—B, relay R^A becomes de-energized, thereby causing the de-energization of relays H^A, G^A, Q^A, and P^A, and causing signal S^A to display a stop indication similar to that illustrated in the drawing at signal S^F, that is, red over red over red. Furthermore, the circuit for device L^A is now interrupted and with only the apparatus thus far described this device would move to its effective position. With systems of the type described it is not unusual to operate trains consisting of two or more cars each provided with apparatus similar to that illustrated in Fig. 3. Under these conditions it would be undesirable to have the device L cooperate with plunger 129 on each of the cars except the first car, and we therefore provide means for holding the device L in its ineffective position until the rear of the train has passed the device, providing the device was in its ineffective position when the train approached the device. This is accomplished by means of an auxiliary circuit for each device L controlled by the associated relay J. For example, when the train passed joint 2^a in approaching point A, relay J^A became de-energized. Since device L^A then occupied its ineffective position, contact 51 was closed and a circuit was closed for device L^A from terminal X^A over back contact 49, of relay J^A, wire 50, contact 51, wires 52 and 48, and operating mechanism of device L^A to terminal Y^A. When the train enters section A—B, therefore, the main operating circuit for device L^A is open but the device is held in its ineffective position by virtue of the circuit just traced, until the rear of the train has passed out of the section to the left of point A. When the train passes point B, device L^B which now occupies its effective position, lifts plunger 129 on the train and initiates a service application of the brakes. Furthermore, the plunger 129 is successively operated as the train passes devices L^C, L^P, and L^E. The lengths of the track sections are so chosen and the severity of the service application of the brakes caused on board the train is so regulated that a train travelling at the maximum permissive speed 70 will be brought to a full stop before reaching point F. Furthermore, the train carried apparatus is so proportioned that if a train travelling at the maximum speed passes point B should incur a brake application, the time 75 80 85 90 95 100 105 110 115 120 125 130

interval required to release the brakes will be so long that successive operations of plunger 129 will take place before the expiration of this time interval in each instance, except that after the train has passed point E the application of the brakes will have so decelerated the train that the time required to charge the reservoir 120 will be consumed before the train reaches point F. The engineer may then release the brakes by moving his valve N to the lap position. But under these conditions, since the brake application has endured since the train passed point B, the train speed will be so reduced that it will be safe to proceed at the low speed at which the train will then be operating.

With only the apparatus thus far described, it will be seen that no matter how low the speed of the train, the train will receive an automatic application of the brakes as soon as it proceeds within four track sections of a hazard here represented by train Z. In systems which must accommodate a large volume of traffic, this feature is undesirable, because it increases the headway, or minimum safe distance between trains. For this reason we have provided means for each section effective when the main operating circuit for the associated track device L is open, to move the device to its ineffective position upon the approach of a train moving at a speed less than that of the maximum speed from which a continued service brake application can bring the train to a full stop short of the hazard which has caused the unsafe traffic conditions that opened the main operating circuit for the device L.

In order to accomplish these results, we provide each section with four timing relays designated by reference characters T, U, V, and W, respectively, with exponents corresponding to the location and controlled in parallel by a back contact 136 of the associated relay J. All of the timing relays are therefore normally de-energized but when a train passes the point of connection of transformer 5 to de-energize the relay J, the corresponding timing relays are all energized. All of the timing relays are slow acting, however, so that an interval of time elapses after the de-energization of relay J before these relays close their front contacts. Furthermore, the four timing relays for each section require different times for their operation so that the relays close their contacts in succession. The parts are so proportioned that the time required for the operation of each relay T is slightly less than that required for a train travelling at some low speed, such as 10 miles per hour, to travel from the insulated joint 2^a to the adjacent trackway device L. In similar manner, the time interval required for each relay U to close its front contact is slightly less than the time required for a train travelling at a somewhat higher speed,

such as 20 miles per hour, to traverse the same distance. In similar manner, relays V and W at each location are adjusted to correspond to different high speeds, such for example, as 30 miles per hour and 40 miles per hour, respectively. 70

Assuming, now, that the train passing device L^B is travelling at the maximum permissive speed, such for example as 50 miles per hour, this train will incur a service application of the brakes at point B and the repeated operation of plunger 129 by devices L^C, L^P, and L^E will cause this application of the brakes to persist to bring the train to a stop before it reaches point F. We will next assume, however, that the train approaching point B is traveling at a lower speed, such for example, as 35 miles per hour. Under these conditions, the timing relay W^B becomes energized before the train reaches point B and a circuit is then closed from terminal X^B, over front contact 33 of relay R^B, wire 34, front contact 35 of relay G^B, wire 36, normal contact 37 of relay H^B, wire 38, front contact 39 of relay P^B, wire 40, reverse contact 41 of relay Q^B, wire 142, front contact 143 of relay W^B, wires 144, 43, 44, 45, 46, 47, 48, and operating mechanism of device L^B to terminal Y^B. It will be plain, therefore, that even though traffic conditions in advance are unsafe, the device L^B will be moved to its ineffective position to prevent an application of the brakes if the speed of the train is below a predetermined safe speed. 85

In similar manner, when the train passes device L^C, this device will be held in its ineffective position if the train speed is below a safe value, but this value is now determined by the timing of relay V^C, the circuit for device L^C passing from terminal X^C, through front contact 33 of relay R^C, wire 34, front contact 35 of relay G^C, wire 36, normal contact 37 of relay H^C, wire 38, back contact 39 of relay P^C, wire 145, front contact 146 of relay V^C, wire 147, 44, 45, 46, 47, and 48, and operating mechanism of device L^C to terminal Y^C. It will therefore be plain that if the train approaching point C is travelling at a speed below 30 miles per hour the device L^C will be moved to its ineffective position before the train passes this device so that no automatic application of the brakes will result. In similar manner, a circuit is prepared at point D from terminal X^D, over front contact 33 of relay R^D, wire 34, front contact 35 of relay G^D, wire 36, reverse contact 37 of relay H^D, wire 160, front contact 148 of relay U^D, wires 45, 46, 47, and 48, and operating mechanism of device L^D to terminal Y^D. This circuit is closed when relay U^D becomes energized. This can, of course, happen only if the speed of the train approaching point D is below the value for which the relay U^D is adjusted, in this case 20 miles per hour. 115

Furthermore, if the train approaching 120

point E is moving at a speed below the value determined by timing relay T^E, the energization of this relay completes a circuit for the device L^E including front contact 33 of relay R^E, back contact 35 of relay G^E and front contact 149 of relay T^E.

It will therefore be plain that at each location the trackway device L is so controlled that under unsafe traffic conditions, a train approaching the hazard which causes unsafe traffic conditions may proceed without incurring an application of the brakes to a point located at a distance in rear of this hazard which depends upon the speed of the train and is equal to the distance required to bring the train to a full stop short of the obstruction.

By making the maximum length of each section only a comparatively small part of the maximum braking distance and by initiating the automatic application at several sections in rear of an occupied section, we have produced a system which permits a material reduction in the headway required for the safe operation of trains.

Under some conditions of operation it may be desirable to arrange the apparatus to ensure that the speed of the train does not exceed some maximum value. This may be accomplished with the apparatus shown in Fig. 4. In this view the timing relay T³ is controlled by relay J³ in such manner that relay T³ becomes energized when a train is approaching point B if the train is travelling at a speed below the maximum permissive speed. With this arrangement, if traffic conditions in advance are safe, a circuit is completed for the operating mechanism of device L^B over front contact 150 of relay P^B, normal contact 151 of relay Q^B and front contact 152 of relay T³ so that the device is moved to its ineffective position before the train passes the device. If, however, the speed of the train exceeds the maximum permissive speed for which the timing relay T³ is adjusted, the device L^B will be in its effective position when the train passes the device and an automatic application of the brakes will result. Furthermore, an automatic application of the brakes will result if a train passes point B when traffic conditions in advance are unsafe, the control of the various relays located at point B being the same as has already been described in connection with Fig. 1.

It is also sometimes desirable to arrange the apparatus to ensure that a train moving through a section immediately in rear of an occupied section shall not proceed at speeds greater than a predetermined low value. To accomplish this result, the section A-B is provided, in Fig. 4, with two relays J¹ and J², receiving energy from transformers 5¹ and 5² connected across insulated joints 2^a at spaced points in the section. Relay J¹ controls a timing relay T¹. Relay J² controls a timing

relay T². The two timing relays T¹ and T² control the trackway devices L¹ and L² which are similar to the other devices L hereinbefore described. Device L² is normally held in its ineffective position by virtue of a circuit including front contact 153 of relay R^B. In similar manner, current is supplied over front contact 153 of relay R^B and front contact 154 of relay J² with the operating mechanism of device L¹. Under safe traffic conditions, then, devices L¹ and L² are at all times held in their ineffective position. When the section to the right of point B is occupied, however, relay R^B is de-energized and the circuits just described for trackway devices L¹ and L² are then open. When timing relay T¹ is energized, current is supplied to device L¹ over its front contact 155 and the parts are so proportioned and arranged that if a train approaching device L¹ is moving at a speed below a predetermined low value, relay T¹ will become energized after this train passes the insulated joint 2^a associated with relay J¹ and before the train reaches device L¹. As a result, the device will be moved to its ineffective position and no automatic application of the brakes will result. Furthermore the closing of relay T¹ completes a circuit for device L² including front contact 155 of relay T¹ and front contact 154 of relay J². When the train passes relay J², this relay becomes de-energized and opens the circuit for device L² at front contact 154 of relay J². At the same time, relay T² is set into operation and if the speed of the train is below the predetermined low value, front contact 156 of relay T² closes to move device L² to its ineffective position before the train reaches the device.

For purposes of explanation we have shown and described our invention applied to a five-block signaling system, but it should be understood that our invention is not limited to this particular arrangement.

Although we have herein shown and described only two forms of railway traffic controlling apparatus embodying our invention, it is understood that various changes and modifications may be made therein within the scope of the appended claims without departing from the spirit and scope of our invention.

Having thus described our invention, what we claim is:

1. Railway traffic controlling apparatus comprising train carried mechanism arranged when actuated to cause an application of the brakes, means on the train for preventing release of the brakes until the expiration of a predetermined time interval following the last actuation of said mechanism, and means located in the trackway and operating under unsafe traffic conditions to cause repeated actuations of said mechanism at distance intervals so short that the train will be

brought substantially to a stop before the brakes can be released.

2. Railway traffic controlling apparatus comprising train carried mechanism arranged when actuated to cause an application of the brakes, means on the train for preventing release of the brakes until the expiration of a predetermined time interval following the last actuation of said mechanism, and tripping devices located at intervals along the trackway and each arranged to actuate said mechanism when a train passes such device under dangerous traffic conditions, said time interval and the distances between said devices being so related that after a brake application has been effected the brakes can be released only if the speed of the train is below a predetermined value.

3. Railway traffic controlling apparatus comprising train carried mechanism arranged when actuated to cause an application of the brakes, means on the train for preventing release of the brakes until the expiration of a predetermined time interval following the last actuation of said mechanism, and a plurality of tripping devices located at intervals along the trackway and each effective under dangerous traffic conditions to actuate said mechanism, the distances between adjacent ones of said devices being less than the distance traversed during said time interval by a train travelling at more than a predetermined low speed.

4. In combination, a section of railway track, a source of energy connected across the rails adjacent one end of the section, an insulated joint in one rail of the section, a winding connected across said joint, a slow acting device located in the trackway and controlled by said winding, a tripping device also located in the trackway and controlled in part by said slow acting device, and train carried governing means controlled in part by said tripping device.

5. In combination, a section of railway track, a source of energy connected with the rails adjacent one end of the section, an insulated joint located at an intermediate point in one rail of the section, a winding connected across said joint, a slow acting device located at one end of the section and controlled by said winding, a tripping device also located in the trackway and controlled in part by said slow acting device, train carried governing means actuated at times by such tripping device to cause an application of the brakes, and means for preventing release of the brakes until the expiration of a predetermined time interval following actuation of said mechanism.

6. In combination with train carried governing mechanism, means located in the trackway for at times controlling said governing mechanism, a plurality of time measuring devices having different time elements

and all set into operation when a train passes a point a measured distance in rear of said means, and apparatus for controlling said means by a different one of said time measuring devices depending on traffic conditions in advance.

7. Railway traffic controlling apparatus comprising train carried mechanism arranged when actuated to cause an application of the brakes, means on the train for preventing release of the brakes until the expiration of a predetermined time interval following the last actuation of said mechanism, means located in the trackway for actuating said mechanism when the train approaches a hazard within the distance required for a brake application to bring the train to a stop, and means for repeatedly actuating said mechanism as the train approaching such hazard traverses distances smaller than that which the train could traverse in said time interval.

8. In combination with a stretch of railway track, a tripping device biased to an effective position and having operating mechanism to move the device to an ineffective position, a circuit for said operating mechanism closed only under safe traffic conditions, time measuring means set into operation when a train approaching said device passes a predetermined point, means controlled by said time measuring means for at times supplying current to said operating mechanism under unsafe traffic conditions, and train carried governing means controlled by said device.

9. In combination a section of railway track, a tripping device located adjacent the exit end of said section, and biased to an effective position, means for holding said device in an ineffective condition when traffic conditions in advance of said section are safe, a source of energy connected across the rails adjacent the exit end of such section, an insulated joint in one rail of said section, a transformer having a primary connected across said joint, a first relay receiving energy from the secondary of said transformer, a slow acting relay controlled by said first relay, means controlled by said slow acting relay for at times moving said device to its ineffective condition when traffic conditions in advance of said section are unsafe, and train carried governing means controlled by said device.

10. In combination, a section of railway track, a tripping device located adjacent the exit end of said section, and biased to an effective position, means for holding said device in an ineffective condition when traffic conditions in advance of said section are safe, a plurality of normally open contacts, means set into operation when a train approaching said device passes a predetermined point and operating to close said contacts at the ex-

pirations of different time intervals, means controlled by said contacts respectively for moving the device to its ineffective condition when traffic conditions in advance of said section are dangerous in different degrees, and train carried governing means controlled by said device.

11. In combination, a stretch of railway track, divided into a plurality of successive sections, a track circuit for each section including a track relay, a polarized home relay and a home repeater relay for each section, means for energizing each said home relay in the normal or reverse direction according as the home repeater relay for the next section in advance is energized or de-energized respectively provided the track relays associated with said home relay and with the section next in advance are both energized, means for energizing each home repeater relay when the associated home relay is energized in either direction, a polarized distant relay and a distant repeater relay for each section, means for energizing each said distant relay in the normal or reverse direction according as the distant repeater relay for the section next in advance is energized or de-energized respectively provided the home relay for such section in advance is energized in the normal direction, means for energizing each distant repeater relay when the associated distant relay is energized in either direction, and a signal for each section controlled by all of the associated relays.

12. In combination, a section of railway track, a source of energy connected across the rails adjacent one end of the section, an insulated joint in one rail of the section, a winding connected across said joint, a tripping device located in advance of said joint, a relay receiving energy from said winding, and means controlled by said relay and by traffic conditions for controlling said device.

13. In combination, a section of railway track, a tripping device adjacent the exit end of said section and normally occupying its effective condition, means effective under safe traffic conditions and operating when a train is approaching said device to move the device to its ineffective position provided the speed of said train is below a predetermined value, a second tripping device located at an intermediate point in the section, means operating under safe traffic conditions to hold said second device in its ineffective position, and means set into operation by a train approaching said second device for moving the device to its ineffective position provided the speed of such train is below a predetermined lower value.

14. Railway traffic controlling apparatus comprising a stretch of railway track divided into a plurality of successive sections, train carried mechanism arranged when actuated to cause an application of the brakes,

means on the train for preventing release of the brakes until the expiration of a predetermined time interval following the last actuation of said mechanism, apparatus for each section for actuating said mechanism when a train enters the section under unsafe traffic conditions, said time interval and the lengths of said sections being so related that after a brake application has been caused the brakes can be released only if the speed of the train is below a predetermined value.

In testimony whereof we affix our signatures.
